2,657,101

PROTECTIVE COLLAR FOR DRILL PIPES

William J. Williams, Odessa, Tex., and James W. E. Hanes, Ventura, Calif., assignors to Ventura Tool Company, Ventura, Calif., a corporation of California

Continuation of application Serial No. 151,921, March 25, 1950. This application November 2, 1951, Serial No. 254,588

18 Claims. (Cl. 308—4)

1

The present invention relates to drill pipe protectors, and more particularly to protective collars composed primarily of rubber or rubber-like material.

This application is a continuation of our application for "Protective Collar for Drill Pipes," Serial No. 151,921, filed March 25, 1950, now abandoned.

An object of the present invention is to provide an improved drill pipe protector capable of being readily mounted on and removed from the drill pipe.

A further object of the invention is to provide a longitudinally split drill pipe protector having axially spaced reinforcing bands embedded therein which are maintained in appropriate longitudinally spaced relation with respect to each other and with respect to the rubber, or rubber-like, protector material in which they are contained or embedded.

Another object of the invention is to provide a split rubber drill pipe protector having locking and reinforcing devices therein, and in which the portions of the protector adjacent its split are held in appropriate position when the protector is clamped on the drill pipe, being prevented from detachment or loosening from the locking and reinforcing devices.

Yet another object of the invention is to provide a split rubber drill pipe protector having locking and reinforcing devices thereon, and in which the end portions of the protector above and below the reinforcing devices are prevented from disengagement or peeling back from the drill pipe on which the protector is mounted.

Still a further object of the invention is to provide an improved rotatable cam lock arrangement for detachably securing a split drill pipe protector collar around and to the drill pipe.

Another object of the invention is to provide a rotatable cam lock arrangement for detachably securing a split drill pipe protector around and to the drill pipe, in which the cam lock is constructed to facilitate its easy assembly in appropriate position in the protector.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense,

2

since the scope of the invention is best defined by the appended claims.

Referring to the drawings:

Figure 1 is a side elevation, with parts broken away, of a drill pipe protector clamped around a drill pipe section;

Fig. 2 is a cross-section taken along the line 2—2 on Fig. 1;

Fig. 3 is an enlarged fragmentary cross-section 10 through the split and locking portions of the protector, with the cam lock arrangement in unlocked position;

Fig. 4 is a view taken generally along the line 4—4 on Fig. 3;

Fig. 5 is a view similar to Fig. 3, but with the cam lock rotated to place the protector in locked position;

Fig. 6 is a fragmentary view of the lock device as seen from the inside thereof.

20 The protector A disclosed in the drawings is adapted to be readily placed around and clamped to a drill pipe B, and also to be easily released and removed therefrom. To accomplish this general purpose, the protector is formed as an annular collar or sleeve 10 made of rubber, or rubber-like, material, having an inside diameter corresponding to the external diameter of the drill pipe B. The rubber collar has tapered end portions 11 to facilitate movement of the drill pipe longitudinally within the well casing (not shown), and to minimize the opportunity of damaging the protector.

25 The rubber portion 10 of the protective collar device is preferably made of one piece, and is provided with a longitudinal split extending completely through its wall, to enable the protector to be opened and closed transversely with respect to a drill pipe B on which it may be mounted. When the protector is closed, the opposite sides 12 of the split portion abut one another and are held in such abutting relation; so as to effectively provide a circumferentially continuous external rubber surface engageable with the well casing (not shown), and also to provide

30 35 40 45 a circumferentially continuous internal surface embracing the drill pipe B.

In order to secure the split rubber protective collar 10 in appropriate position around and upon the drill pipe, a plurality of flexible metallic bands 13 are embedded in the rubber sleeve or collar, and these bands are preferably longitudinally spaced from one another and are also spaced longitudinally inward from the upper and lower ends 11 of the rubber collar. Each band is 50 55 split and has a fitting or fastening member 14 or

15 secured to each end portion on opposite sides of the split. In effect, the fitting or fastening members 14, 15 may be considered as continuations or parts of the band 13 itself.

One end of the band 13 is received in an arcuate slot 16 formed in one of the fittings 15, this fitting having inner and outer arcuate flanges 17, 18 adjacent the split portion of the rubber collar, defining an arcuate groove or slot 19 therebetween. The other end of the band is secured to the opposite fitting 14, being received within an arcuate slot 20 in the latter. This fitting 14 is provided with an arcuate tongue 21 adapted to be positioned within the arcuate slot 19 of the other fitting 15, whenever the band 13 and collar 10 are clamped around a drill pipe B.

The collar 10 and bands 13 are contracted and clamped around and to the drill pipe by a rotatable cam type of lock device 22. This device includes a member 23 rotatably mounted in one of the fittings 14 and having a cam jaw or eccentric pin 24 received within an opening 25 in the other fitting 15. As specifically disclosed in the drawings, the inner arcuate flange 17 of the fittings 15 extends circumferentially beyond the outer flange 18 of this fitting, and has an opening 25 therein which is generally ovate or elliptical in shape, with the greater dimension of the opening extending vertically. The cam locking member 23 has its eccentric pin 24 received within this opening, the locking member itself being rotatable within a circular or cylindrical opening 26 in the tongue 21 of the fitting 14. Endwise movement of the locking member 23 relative to the tongue 21, along the axis of the locking member 23, is prevented by providing an inner flange 27 on the locking member, which is received within a counterbore 28 in the fitting and engaging an inner shoulder 29 provided by the base of the counterbore. Such engagement of the flange 27 with the shoulder 29 prevents laterally outward movement of the eccentric member 23 with respect to the fitting 14 and its tongue 21. Inward movement of the cam member 23 with respect to the latter parts is prevented by an outer ring or sleeve 30 fitting around the reduced diameter portion 31 of the cam locking member, the inner end of this ring or sleeve 30 engaging a step or shoulder 32 formed on the lock member 23 and also engaging a shoulder 33 provided by the external surface of the tongue 21 of the fitting. The ring 30 is made of a comparatively malleable metal; so that, after having been slipped over the reduced diameter portion 31 of the cam locking member and into engagement with the locking member shoulder 32 and exterior 33 of the tongue, the outer part 34 of the ring 30 can be peened, or otherwise forced, into a peripheral groove 35 formed in the locking member 23. When such peening, or forcing, of the ring 30 has been accomplished, the ring is effectively secured to the locking member 23. As a result, the inner end of the ring engages the outer surface 33 of the tongue 21, to prevent inward axial movement of the cam locking member 23, whereas the flange 27 of the latter engages the shoulder 29 at the inner end of the counterbore 28, to prevent outward movement of the locking member 23.

The rubber collar 10 has a pocket 36 into which the inner arcuate flange 17 of the fitting 15 can pass when the band 13 is drawn around the drill pipe. The rubber collar on opposite sides of its split is also provided with opposed arcuate

or semi-circular recesses 37 in which the cam locking member 23 is received. These recesses 37 extend to the exterior of the collar member 10, to permit access to the cam locking member 23 by a suitable wrench or other tool (not shown) adapted to fit within the polygonal or non-circular socket 38 formed in the cam locking member. When the cam locking member 23 is rotated, to draw the opposed ends of each band and its fitting toward each other, the cam locking member 23 and its outer retainer ring 30 are received within an arcuate recess or notch 39 provided in the outer flange 18 of the fitting 15.

15 The eccentric cam jaw or pin 24 has opposed flat sides 40 which are interconnected by curved convex surfaces 41. Similarly, the sides 42 of the opening 25 in the inner arcuate flange 17 are also preferably flat and vertical, the bottom 43 of the opening interconnecting these sides preferably being curved in concave fashion, while the upper end of the opening is defined by a curved corner pocket 44 merging into one of the flat sides 42 of the opening and conforming to the curvature 41 of the pin 24. The other side 42 of the opening merges into an arcuate corner 45 running into the upper straight side 46 of the opening, which, in turn runs into the corner 44.

As disclosed in Figs. 3 and 4, the band 13 is in open position, with the eccentric pin 24 engaging one side end 42 of the opening 25 in the inner arcuate flange 17. This position is suitably indicated by a radial notch 47 formed in the outer end of the cam locking member 23 in longitudinal alignment with the cam jaw or eccentric pin 24. A suitable bar or wrench (not shown) is placed in the polygonal socket 38 in the cam member 23 and the latter rotated in a clockwise direction, as seen in Fig. 4, which causes the cam 24 to shift the inner arcuate flange 17 into the pocket 36 and to dispose the tongue 21 of the other fitting 14 in the arcuate slot 19 between the inner and outer flanges 17, 18. Such rotation occurs until the opposite side 40 of the pin engages the flat side 42 of the opening, with the upper curved end 41 of the pin disposed in the corner pocket 44 of the opening, as shown in Figs. 5 and 6, as well as in Figs. 1 and 2. When in this position, the center of the pin 24 and axis of the locking member 23 lie in the central plane of the band 13 normal to the axis of the collar 10, there being no components of force passing to one side of the axis of the locking member 23 that can inadvertently release it from its locking position. When the parts are in this locked position, the band 13 and the rubber collar 10 have been fully contracted around the drill pipe, with the rubber collar clamped upon the latter. At this time, the opposed longitudinal edges 12 of the rubber collar abut one another firmly, the only openings present being the arcuate recesses 37 provided for the cam locking member 23. The rubber protector material is circumferentially continuous at all of the regions of the collar 10, both externally and internally thereof. Any tendency for the band and collar to expand is resisted by the cam device, since it provides a self-locking arrangement. Thus, as stated above, the expanding force passes through the axis of rotation of the cam locking member 23, and, therefore, is incapable of rotating the latter.

As aforementioned, a plurality of longitudinally spaced band members 13 and attached fittings 14, 15 are provided, each combination being a

duplicate of the other and being operated in exactly the same manner. They may each have holes 50 therethrough into which the rubber material 10 can flow during the molding of the device, and thereby securely and permanently anchor the bands 13 to the rubber collar 10. In addition, the rubber collar 10 will have circumferentially spaced longitudinal recesses 51 therein, which are formed as a result of parts of the mold extending into the mold cavity, to hold the bands 13 in appropriate position during the molding operation.

The bands 13 are also held in longitudinal spaced relation by longitudinally extending bars or straps 52, there being a bar or strap disposed on each side of the split portion of the rubber collar. As disclosed in the drawings, the strap member 52 is of generally L-shaped or angled section having a generally circumferential flange portion 53 secured to a fitting 14 or 15 by rivets 54, which also pass through the band 13, to secure the latter to the fitting. Each strap has a radial flange portion 55 extending from the circumferential flange portion 53, which is embedded in the rubber collar material. It is to be noted that the strap 52 itself extends longitudinally beyond the upper end of the upper band 13 and the lower end of the lower band 13, being disposed within the tapered end portions 11 of the rubber collar.

The straps 52, as noted above, will also aid in holding the bands in longitudinal spaced relation. In addition, their generally radial flanges 55 resist outward displacement of the rubber collar material at opposite sides of the longitudinal collar split. When each cam locking member 23 is rotated to locked position, the longitudinal edges 12 of the rubber collar member are brought into bearing engagement with each other and may tend to bulge outwardly, or cause a tendency for the rubber collar 10 to peel circumferentially from the fittings 14, 15. The generally radial flanges 55 of the straps effectively lock the marginal portions of the rubber collar on opposite sides of the split to the bands, and prevent such peeling or stripping of the rubber material from the band 13, and, more particularly, from its fittings 14, 15.

In addition to the foregoing purposes, the projection of the straps 52 into the end portions 11 of the collar also causes them to resist displacement of such end portions from an appropriately clamped position upon the drill pipe B. They also resist any tendency for the end portions 11 to be lifted or pried from the drill pipe, as a result of encountering foreign substances in the well bore.

The inventors claim:

1. A protective collar of the class described, including a relatively long cylindrical collar member of yieldable material split substantially longitudinally at one side, a plurality of split flexible metallic bands extending circumferentially thereof and spaced longitudinally from each other with respect to the axis of the collar, the ends of the bands being separated at the split portion of the collar, straps, extending longitudinally of the collar, connecting the bands in axially spaced relation, and a lock member adjustably connected to one end of each of the bands and adapted to be detachably connected to the other end of the corresponding band in such a manner as tightly to clamp the collar around a pipe at each of the bands.

2. A protective collar of the class described, in-

cluding a relatively long cylindrical collar member of yieldable material split substantially longitudinally at one side, a plurality of split flexible metallic bands extending circumferentially thereof and spaced longitudinally from each other with respect to the axis of the collar, the ends of the bands being separated at the split portion of the collar, a strap secured to and connecting said bands in axially spaced relation, said strap being located at the split portions of the bands and of the collar, and a lock member adjustably connected to one end of each of the bands and adapted to be detachably connected to the other end of the corresponding band in such a manner as tightly to clamp the collar around a pipe at each of the bands.

3. A protective collar of the class described, including a relatively long cylindrical collar member of yieldable material split substantially longitudinally at one side, a plurality of split flexible metallic bands extending circumferentially thereof and spaced longitudinally from each other with respect to the axis of the collar, the ends of the bands being separated at the split portion of the collar, a strap, of angular cross-section, secured to and connecting each of said bands in axially spaced relation, said strap being located at the other side of the split portions of the bands and of the collar, one of the flanges of each strap extending radially outwardly, and a lock member adjustably connected on one end of each of the bands and adapted to be detachably connected to the other end of the corresponding band in such a manner as tightly to clamp the collar around a pipe at each of the bands.

4. A protective collar of the class described, including a cylindrical collar member of yieldable material split substantially longitudinally at one side, a split flexible metallic band extending circumferentially thereof, one end portion of the band having a cam opening, which opening includes a pocket portion at the circumference of the opening and to one side of the center line of the opening, and a take-up member rotatably mounted on the other end portion of the band, the take-up member having an elongated cam jaw adapted to be inserted into the opening and to be rotated by the take-up member from one side to the opposite side of the axis of the take-up member, for drawing together the split portions of the band, the leading end of the elongated cam jaw, as the same is rotated to the band-closing position, terminating in said pocket portion of the opening for locking the collar in a closed position, the elongation of the cam jaw being transverse with respect to the circumferential extent of the band when said cam jaw is in said pocket portion.

5. A protective collar of the class described, including a cylindrical collar member of yieldable material split substantially longitudinally at one side, a split metallic band extending circumferentially thereof, one end of the band having a transverse opening, which opening includes a pocket portion at the circumference of the opening and to one side of the center line of the opening, and a take-up member rotatably mounted on the other end portion of the band, said take-up member having a transversely elongated cam jaw adapted to be inserted into the opening, the rotation of the take-up member causing said cam jaw to be shifted from one position to a diametrically opposite position with respect to the axis of the take-up member for

drawing the end portions of the band relative to each other, the leading end of the elongated cam jaw, as the same is rotated to the band-closing position, terminating in said pocket portion of the opening for locking the collar in a closed position. 5

6. A protective collar of the class described, including a cylindrical collar member of yieldable material split substantially longitudinally at one side, a split flexible metallic band extending circumferentially thereof, one end of the band having a transverse opening, which opening includes a pocket portion at the circumference of the opening and to one side of the center line of the opening, and a take-up member rotatably mounted in the other end portion of the band on an axis transverse to the axis of the collar, said take-up member having at its inner end a transversely elongated cam jaw adapted to be inserted into the opening, the rotation of the take-up member causing said cam jaw to be shifted from one position to the diametrically opposite position with respect to the axis of the take-up member for drawing the end portions of the band relative to each other, the leading end of the elongated cam jaw, as the same is rotated to the band-closing position, terminating in said pocket portion of the opening for locking the collar in a closed position. 20

7. A protective collar of the class described, including a cylindrical collar member of yieldable material split substantially longitudinally at one side, a split flexible metallic band extending circumferentially thereof, one end portion of the band having a cam opening, which opening includes a pocket portion at the circumference of the opening and to one side of the center line of the opening, and a take-up member rotatably mounted on the other end portion of the band, the take-up member having an elongated cam jaw adapted to be inserted into the opening and to be rotated by the take-up member from one side to the opposite side of the axis of the take-up member for drawing together the split portions of the band, the leading end of the elongated cam jaw, as the same is rotated to the band-closing position, terminating in said pocket portion of the opening for locking the collar in a closed position, the elongation of the cam jaw being transverse with respect to the circumferential extent of the band when said cam jaw is in said pocket portion, and interlocking lugs extending substantially circumferentially beyond the end portions of the band for retaining the cam jaw within said opening. 50

8. A protective collar of the class described, including a cylindrical collar member of yieldable material split substantially longitudinally at one side, a split flexible metallic band extending circumferentially thereof, one end of the band having a transverse opening, which opening includes a pocket portion at the circumference of the opening and to one side of the center line of the opening, a take-up member rotatably mounted on the other end portion of the band, said take-up member having a transversely elongated cam jaw adapted to be inserted into the opening, the rotation of the take-up member causing said cam jaw to be shifted to the diametrically opposite position with respect to the axis of the take-up member for drawing the end portions of the band relative to each other, the leading end of the elongated cam jaw, as the same is rotated to the band-closing position, terminating in said pocket portion of the opening for locking the collar in a 75

closed position, and interlocking lugs extending substantially circumferentially beyond the end portions of the band for retaining the cam jaw within said opening. 8

9. A collar, including a split band, one end portion of the band having a cam opening, and a take-up member rotatably mounted on the other end portion of the band on an axis extending transversely of the band, the take-up member having a cam jaw extending inwardly and adapted to be inserted into the opening and to be rotated by the take-up member in said opening, said take-up member comprising a cylinder rotatably mounted in a bore of the band, said cylinder having an annular flange at its inner portion fitting into an annular recess concentric with the bore, the inner side of the flange being substantially flush with the inner side of the band and the cam jaw extending inwardly from the peripheral portion of the flange, the outer portion of the cylinder being reduced in diameter, and a retaining ring mounted on the reduced diameter portion and secured in position thereon. 10

10. A protective collar of the class described, including a cylindrical collar member of yieldable material split substantially longitudinally at one side, a split flexible metallic band extending circumferentially thereof, one end portion of the band having a cam opening, and a take-up member rotatably mounted on the other end portion of the band on an axis extending transversely of the band, the take-up member having a cam jaw extending inwardly and adapted to be inserted into the opening and to be rotated by the take-up member in said opening, said take-up member comprising a cylinder rotatably mounted in a bore of the band, said cylinder having an annular flange at its inner portion fitting into an annular recess concentric with the bore, the inner side of the flange being substantially flush with the inner side of the band and the cam jaw extending inwardly from the peripheral portion of the flange, the outer portion of the cylinder being reduced in diameter, and a retaining ring mounted on the reduced diameter portion and secured in position thereon. 25

11. A collar, including a split band, one end portion of the band having a cam opening, and a take-up member rotatably mounted on the other end portion of the band on an axis extending transversely of and outwardly from the band, the take-up member having a cam jaw extending inwardly and adapted to be inserted into the opening and to be rotated by the take-up member in said opening, said take-up member comprising a cylinder rotatably mounted in a bore of the band, said cylinder having an annular flange at its inner portion fitting into an annular recess concentric with the bore, the inner side of the flange being substantially flush with the inner side of the band and the cam jaw extending inwardly from the peripheral portion of the flange, the outer portion of the cylinder being reduced in diameter and provided with an annular groove intermediate its ends, and a retaining ring mounted on the reduced diameter portion, the outer portion of the ring being pressed into said groove. 35

12. A protective collar of the class described, including a generally cylindrical collar member of elastic material split substantially longitudinally at one side, a plurality of split flexible bands extending circumferentially of the collar and spaced longitudinally from each other, the ends of the bands being separated at the split 40

portion of the collar, a strap connecting the bands in axially spaced relation, and a lock member rotatably mounted on one end of each band and detachably connected to the other end of the same band to clamp the collar around a pipe upon rotation of said lock member.

13. A protective collar of the class described, including a generally cylindrical collar member of elastic material split substantially longitudinally at one side, a plurality of split flexible bands extending circumferentially of the collar and spaced longitudinally from each other, the ends of the bands being separated at the split portion of the collar, a strap connecting the bands in axially spaced relation, said strap including a reinforcing member extending laterally of said collar and embedded therein, and a lock member rotatably mounted on one end of each band and detachably connected to the other end of the same band to clamp the collar around a pipe upon rotation of said lock member.

14. A protective collar of the class described, including a generally cylindrical collar member of elastic material split substantially longitudinally at one side, a plurality of split flexible bands extending circumferentially of the collar and spaced longitudinally from each other, the ends of the bands being separated at the split portion of the collar, a strap connecting the bands in axially spaced relation, said strap extending longitudinally beyond said bands into the end portions of said collar member, and a lock member rotatably mounted on one end of each band and detachably connected to the other end of the same band to clamp the collar around a pipe upon rotation of said lock member.

15. A protective collar of the class described, including a generally cylindrical collar member of elastic material split substantially longitudinally at one side, a flexible band extending circumferentially of the collar, the ends of the band being separated at the split portion of the collar, a reinforcing member secured to the band adjacent an end of the band and extending laterally of said collar and embedded therein, and a lock member rotatably mounted on one end of each band and detachably connected to the other end of the same band to clamp the collar around a pipe upon rotation of said lock member.

16. A protective collar of the class described, including a generally cylindrical collar member of elastic material split substantially longitudi-

nally at one side, a flexible band extending circumferentially of the collar, the ends of the band being separated at the split portion of the collar, a reinforcing member secured to the band at an end portion thereof and extending longitudinally beyond said band into the end portions of said collar member, and a lock member rotatably mounted on one end of said band and detachably connected to the other end of said band to clamp the collar around a pipe upon rotation of said lock member.

17. A collar, including a split band, one end portion of the band having a cam opening, and a take-up member rotatably mounted on the other end portion of the band for rotation about an axis extending transversely of the band, said member having a cam element insertable in said opening to engage said one end portion and contract said band upon rotation of said take-up member, said take-up member comprising a cylindrical portion rotatably mounted in the band, a flange on one side of said portion engageable with one side of said band, said take-up member having a reduced diameter portion on the other side of said cylindrical portion, and a retaining member on said reduced diameter portion engageable with the other side of said band and secured to said take-up member.

18. A collar, including a split band, one end portion of the band having a cam opening, and a take-up member rotatably mounted on the other end portion of the band for rotation about an axis extending transversely of the band, said member having a cam element insertable in said opening to engage said one end portion and contract said band upon rotation of said take-up member, said take-up member comprising a cylindrical portion rotatably mounted in the band, a flange on one side of said portion engageable with one side of said band, and a retaining member secured to said take-up member and engageable with the other side of said band.
